UNITED STATES PATENT OFFICE.

JOHN R. WRIGHT, OF WHEELING, MISSOURI.

ADJUSTABLE SAG-GATE.

1,341,963.

Specification of Letters Patent.

Patented June 1, 1920.

Application filed September 8, 1919. Serial No. 322,320.

To all whom it may concern:

Be it known that I, JOHN R. WRIGHT, a citizen of the United States, residing at Wheeling, in the county of Livingston and 5 State of Missouri, have invented a new and useful Adjustable Sag-Gate, of which the following is a specification.

This invention relates to gates one of its objects being to provide a gate having simple and efficient means thereon whereby it 10 can be adjusted angularly to any desired position and then securely fastened, thus to allow small animals to leave an inclosure and at the same time act as a bar for large 15 live stock.

Another object is to provide adjusting means which is easily operated and easy to install.

With the foregoing and other objects in 20 view which will appear as the description proceeds, the invention consists of certain novel details of construction and combinations of parts which will be hereinafter more fully described and pointed out in the claim 25 it being understood that various changes may be made in the construction and arrangement of the parts without departing from the spirit or sacrificing any of the advantages of the invention as set forth in the 30 appended claim.

In the accompanying drawings the preferred form of the invention has been shown.

In said drawings—

Figure 1 is an elevation of a gate having 35 the present improvements applied thereto, one position being indicated by broken lines.

Fig. 2 is a section through the clamp.

Referring to the figures by characters of 40 reference 1 designates a post to which is hinged a gate 2 made up of vertical members 3 and parallel rails 4, said rails and the members 3 being pivotally connected, as indicated at 5 so that the gate can be adjusted angularly by swinging the rails about 45 their connections with the members 3. Pivotally connected to two of the rails 3 is a

strip 6 and a rod 7 is pivotally connected at its ends to this strip 6 and to one of the members 3, said rod being parallel with the rails. A split sleeve 8 is slidably mounted 50 on the rod 7 and has ears 9 connected by a bolt 10. Mounted on this bolt with the ears 9 extending between them are eyes formed at the lower ends of brace rods 11 and the upper ends of the rods are pivotally connected to the upper end portion of the member 3 at the hinge end of the gate. Obviously by loosening the bolt 10 the sleeve 55 will be loosened on the rod 7 and can be slid thereon, thereby causing the rods 11 to 60 pull or to push on the end of the gate so as to cause the rails 4 to swing upwardly or downwardly relative to the post. When the rails have been brought to desired angles the bolt 10 can be tightened and the several 65 parts will be held together against relative movement.

What is claimed is:—

A gate including pivotally connected vertical and rail members, a strip pivotally 70 connected to certain of the rail members and parallel with the vertical members, a rod pivotally connected to said strip and one of the vertical members and extending between and parallel with certain of the 75 rails, a split sleeve slidably mounted on the rod, said sleeve having ears extending therefrom, brake rods extending to opposite sides of the sleeve, means extending through said rod and the ears for pivotally connecting 80 them, and a connection between the brake rods and the upper end of one of the vertical members, said connection between the brake rods and the ears being adjustable to bind the sleeve upon its guide rod. 85

In testimony that I claim the foregoing as my own, I have hereto affixed my signature.

JOHN R. WRIGHT.
